INVENTOR
J. O. Cadieux
ATTORNEY

UNITED STATES PATENT OFFICE.

JOSEPH O. CADIEUX, OF MERIDEN, CONNECTICUT, ASSIGNOR TO THE CONNECTICUT TELEPHONE & ELECTRIC COMPANY, OF MERIDEN, CONNECTICUT, A CORPORATION OF CONNECTICUT.

ELECTRIC VIBRATOR.

Application filed October 28, 1921. Serial No. 511,140.

To all whom it may concern:

Be it known that I, JOSEPH O. CADIEUX, a citizen of the United States of America, residing at Meriden, Connecticut, have invented a new and useful Electric Vibrator, of which the following is a specification.

The main object of my invention is to provide a simple, reliable construction which can be economically made and which will not get out of adjustment accidentally or through deterioration with time.

The invention is shown as applied to one type of bell. It should be understood that the invention is applicable to other buzzer or ringer movements.

Figure 1 is a plan view of a construction embodying the improvements of my invention;

Fig. 2 is a face view of the vibrator proper;

Fig. 3 is a perspective view of the spring member;

Fig. 4 is a perspective view of the armature;

Fig. 5 is a perspective view of the armature supporting member;

Fig. 6 is a side view and partial section showing the electro-magnet and method of supporting the stationary contact;

Fig. 7 is a perspective view of a bracket for supporting the magnets; and

Fig. 8 is a sectional view of the adjusting means for the armature.

In the form shown, the base 10 supports a gong top or bell 11 in any suitable manner. The electro-magnet is supported by a bracket 12, which is secured to the base by a screw 13. The bracket may be slotted, as at 14, and provided with a lug 14' centered in the base 10, so as to act as a pivot and permit the bracket and the parts supported by it to be adjusted by a swinging movement to bring the parts into the desired position. The cores 15, 15 of the magnet are riveted to the bracket 12 and carry a yoke 16 at their opposite ends. This yoke, the cores and the bracket 12 form a rigid support for the coil windings and hold them permanently in their proper relative positions.

The yoke is provided with ears 17, in

which the pins 18 of the armature 19 are pivoted. The armature may be provided with a hammer arm 20 when the mechanism is used as a striker or ringer for a bell or the like. A non-metallic stop 21 may be provided on the armature to prevent said armature from sticking to the magnet core.

A spring member 22 performs the double function of a tensioning device for the armature and also the movable member of the make-and-break contact. One end is perforated at 23 to allow for the free passage of the shank of an adjusting screw 24. The screw has a threaded seat in the end 25 of the yoke 16, so that, by rotating the screw, the end of the spring 22 may be flexed to provide the necessary tension for operation. The screw may be provided with any suitable form of head 26. In the back of the head of the screw is a series of recesses 27 adapted to receive bosses 28 formed on the end of the spring 22. These recesses and bosses hold the screw from accidental rotation and yet permit the screw to be turned when it is desired to tighten or loosen the spring.

The opposite end of the spring 22 is provided with a contact 29, which is adapted to make or break the circuit from the contact 30, which is carried by the arm 31 of the yoke but insulated therefrom.

It will be seen that the construction is such that it is impossible for the coils to pull apart. The construction of the yoke and method of supporting the armature and spring are such as to keep the contact points in proper alignment. It is also possible to adjust the action by means of the screw 24, instead of by the use of pliers for bending springs, as is frequently done in other constructions. By loosening the screw 13 and adjusting the bracket 12 the ring mechanism may be located on the base to accommodate a larger or smaller bell.

I claim:

1. In an electric vibrator, an electromagnet, a yoke carried thereby, an armature pivotally carried by said yoke, a spring member secured to said armature, an adjusting screw 100

passing through one end of said spring and said ears, an arm connected to said yoke, a adjustable in said yoke, and a stationary spring connected to said armature, a screw contact also carried by said yoke and co-acting with the opposite end of said spring. 10

5. 2. In an electric vibrator, a magnet, a yoke carried thereby and having ears integral therewith, an armature pivotally carried by

co-acting with one end of said spring and with said yoke, and a contact carried by said arm, the opposite end of said spring co-acting with said contact.

JOSEPH O. CADIEUX.
